UNITED STATES PATENT OFFICE.

JOSEPH V. WECKBAUGH, OF ST. LOUIS, MISSOURI, ASSIGNOR TO NAGLE RE BLADE KNIFE COMPANY, OF NEWARK, NEW JERSEY, A CORPORATION OF NEW JERSEY.

METHOD FOR INSERTING RIVETS IN REBLADE-KNIVES.

1,109,094.

Specification of Letters Patent.

Patented Sept. 1, 1914.

Original application filed December 5, 1911, Serial No. 664,126. Divided and this application filed August 25, 1913. Serial No. 786,584.

To all whom it may concern:

Be it known that I, JOSEPH V. WECKBAUGH, a citizen of the United States, residing in the city of St. Louis and State of Missouri, have invented a new and useful Method for Inserting Rivets in Reblade-Knives; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to a method for inserting rivets in re-blade knives, or knives so constructed that the blades are readily removable.

This invention is a division of my former 20 application, Serial No. 664,126, filed December 5, 1911, and is particularly intended for inserting the female member of a rivet composed of male and female parts interlocked by a screw thread.

25 The method consists in applying the female member of the rivet to the reduced extremity of the tool which is pointed at one end, inserting the pointed end of the tool first through the rivet holes of the blade and 30 handle of the knife until the female member of the rivet takes its proper position, then removing the tool and inserting the male member of the rivet, which has a threaded portion which is the counterpart of the 35 threaded socket in the female member.

Before entering into a more detailed description of the method, I will first describe a suitable mechanical construction for carrying out or practising the invention.

40 In the accompanying drawing, forming a part of this specification I have illustrated a suitable device which may be employed in practising this method, this device being also illustrated in connection with the handle, blade and main spring of a knife of the 45 construction to which the invention is applicable.

In this drawing, Figure 1 is a detail view 50 of a tool adapted for use in this connection showing the same before it has been connected with the female member or tubular part of the rivet. Fig. 2 is a detail view of the female rivet member. Fig. 3 is a similar view of the male member. Fig. 4 is a view

showing the needle connected with the female member of the rivet ready for use. Fig. 5 is an elevation of a knife showing the position of the blade with relation to the handle when the blade is first inserted and before the main spring has been pressed 60 rearwardly to cause the perforation in the tang of the blade to register with the perforation of the handle members. Fig. 6 is a view illustrating the manner of using the needle in connection with the handle and 65 blade of the knife, the last named parts being shown in section, taken on the line 6—6, Fig. 5, but shown on a larger scale. Fig. 7 is a similar view showing the needle at its limit of movement, the female member 70 of the rivet being in place. Fig. 8 is a sectional view similar to Fig. 7, showing the two rivet members connected.

In this drawing, the same reference characters indicate the same parts in all the 75 views.

Let the numeral 5 designate the needle whose cylindrical body portion 6 is equal in diameter to the rivet to be used in connecting a blade 7 with a handle 8. One extremity of this needle is cone-shaped as shown at 9 while its opposite extremity is reduced and preferably plain or unthreaded as shown at 10, and of such size that it readily enters the threaded socket of the 85 rivet without interfering with or injuring the threads thereof. Hence, this form of construction is illustrated in the drawing. As just intimated, this part 10 is adapted to enter the threaded socket formed in a female 90 rivet member 12, whose head is upset and provided with a nick, making it practicable to use a screw driver in connecting the same with the male member 13 of the rivet.

Preparatory to beginning the process or 95 method covered in this application, the tang of the blade 7 is passed into the extremity of the handle with which it is to be connected, as far as the main spring will permit without forcing the latter rearwardly. Under 100 these circumstances, there is a small part 14 of the perforation in the tang 15 of the blade which overlaps or registers with a perforation 16 in the handle extremity. As soon as this is done, and the female member 105 of the rivet is applied to the extremity 10 of the needle, the cone-shaped extremity 9 of the latter, is inserted in the registering

portions of the perforation 16 and 17 in the blade and handle, respectively, and the needle is forced forwardly to cause its body portion 6 to enter the perforations of the 5 blade and handle, and as the part 6 of the needle is of the same size as the female member 12 of the rivet, this member is readily inserted in the said perforations. The needle 5 is then disconnected from the female 10 member of the rivet and the male member of the latter which is also provided with a screw head is inserted therein.

Having thus described my invention, what I claim is:

15 1. A method for inserting rivets in re-blade pocket knives, where in the absence of a rivet, the spring of the handle tends to force the rivet hole of the blade out of line with the holes of the handle, consisting in applying the female member of the rivet to 20 the reduced extremity of a tool, inserting

the tool through the rivet holes in the blade and handle of the knife until the female member of the rivet takes its proper position, then removing the tool and inserting 25 the male member of the rivet.

2. A method for inserting rivets in re-blade pocket knives where in the absence of a rivet, the spring of the handle tends to force the rivet hole of the blade out of line 30 with the holes of the handle, consisting in applying a rivet member to the extremity of the tool, inserting the tool through the rivet holes in the blade and handle of the knife until the said rivet member takes its proper 35 position, and then removing the tool.

In testimony whereof I affix my signature in presence of two witnesses.

JOSEPH V. WECKBAUGH.
